US0D1069517S

(12) **United States Design Patent** (10) Patent No.: **US D1,069,517 S**
(45) Date of Patent: ** Apr. 8, 2025

(54) **DEVICE HOLDER ATTACHMENT FOR A
HAND MIXER**

(71) Applicant: **WHIRLPOOL CORPORATION**,
Benton Harbor, MI (US)

(72) Inventors: **John W. McConnell**, St. Joseph, MI
(US); **Brandon Tyler Mock**, St. Joseph,
MI (US); **Nicholas Hill Schutte**, St.
Joseph, MI (US)

(73) Assignee: **WHIRLPOOL CORPORATION**,
Benton Harbor, MI (US)

(**) Term: **15 Years**

(21) Appl. No.: **29/900,570**

(22) Filed: **Aug. 22, 2023**

Related U.S. Application Data

(63) Continuation of application No. 29/806,818, filed on
Sep. 7, 2021, now Pat. No. Des. 1,001,619.

(57) **CLAIM**

The ornamental design for a device holder attachment for a
hand mixer as shown and described.

DESCRIPTION

FIG. 1 is a perspective view of a device holder attachment
for a hand mixer according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in even broken line form
no part of the claimed design.

Dash-dot-dash broken lines adjacent un-shaded areas repre-
sent bounds of the claimed design and form no part of the
claimed design themselves.

1 Claim, 7 Drawing Sheets
